UNITED STATES PATENT OFFICE

MAX SCHMID, OF NUERMBERG, GERMANY

PAPER CARRIAGE FOR TYPEWRITING MACHINES

Application filed January 15, 1929, Serial No. 332,647, and in Germany April 13, 1928.

This invention relates to a construction of the paper-carriage of such type-writing machines, in which the printing of the types is produced by the platen striking against the types, and it has for its object to considerably simplify and consequently make cheaper the manufacturing of the carriage.

This is obtained according to the invention essentially by making the casing of the platen slide on transverse rods of a supporting frame extending through the side walls of the casing, said supporting frame being guided on rods arranged transversely to the axis of the platen and fixed on the machine frame, said support being shiftable in forward and backward direction.

An embodiment of the invention is illustrated by way of example in the accompanying drawing in which:

Fig. 1 is a vertical cross section on line 1—1 of Fig. 2 and

Fig. 2 a front elevation, partly in section on line 2—2 of Fig. 1.

Behind the type carrier *b* rotatable around a vertical axle *a* the platen *c* is arranged in such a manner that it is adjustable in vertical direction by means of its axle *e* engaging with longitudinal slots *f* in the two end walls *d*. Through the end walls *d* of the casing of the platen extend two transverse rods *g* which are fixed on the upwardly bent flaps *h* of a carrying bar *i* of U-shaped cross section. In downwardly directed longitudinal flanges *k* of this carrying bar *i* two carrying rods *l, m* are located, which are fixed in the vertical standards *n, o* of the typewriting machine so the the paper carriage can be shifted in a simple manner forward and backward on the rods *l, m* but shifted in lateral directions on the guide rods *g*.

According to the invention the arrangement is such that the guide rods serving for the lateral shifting are utilized directly for the secure insertion and catching of the paper sheet as on these guide rods, between the end walls *d* of the platen carriage, brass sleeves *p* are loosely mounted so that they can rotate and be shifted in axial direction when the carriage is being shifted.

On these brass sleeves *p* fluted rubber rolls *q* are mounted.

A positive pressing of the carriage against the rubber sleeves, ensuring the catching of the paper sheet, is obtained thereby that the paper holder *s* controlled by a spring *r* and which carries on a continuous axle *t* rubber rolls *u*, presses against the platen *c*, whereby this platen is pressed against the guide rolls *q*.

In order to obtain the guide faces necessary for the paper sheet to be inserted behind the platen, tongues *v* and *w* are stamped out of the bottom plate and back wall of the carriage and bent upwards and forwards respectively so that their ends are directed towards the platen.

In this manner the manufacturing of the guide of the carriage and of the platen is considerably simplified without prejudice to the durability and to the security of the service.

I claim:—

1. A carriage for type-writing machines in which the printing of the types is produced by the platen striking against the stationary types, comprising in combination with the machine frame and the platen, a casing for the platen having end walls, a supporting frame for said casing, transverse rods mounted in the end walls of said supporting frame said casing being shiftable on these transverse rods, and rods transversely to the axle of the platen extending through the long walls of said supporting frame so that said frame can be shifted on said latter rods.

2. A carriage for type-writing machines in which the printing of the types is produced by the platen striking against the stationary types, comprising in combination with the machine frame and the platen, a casing for the platen having end walls having vertical slots guiding the axle of said platen, a supporting frame for said casing, transverse rods mounted in the end walls of said supporting frame said casing being shiftable on these transverse rods, brass sleeves loosely mounted on said transverse rods and situated between the end walls of said casing, rubber rolls on said brass sleeves, rods transverse to

the axle of the platen extending through the long walls of said supporting frame so that said frame can be shifted on said latter rods, and a spring controlled paper holder by which said platen is positively pressed against said rubber rolls.

3. In a carriage for type-writing machines, as claimed in claim 1, in combination with the platen and a casing for said platen, 10 tongues stamped out of the bottom plate and back plate of said casing and curved at the end to serve as guide faces for the insertion of the paper sheet.

In testimony whereof I affix my signature.
MAX SCHMID.
